C. J. AND G. J. CLEFTON,
ACETYLENE GENERATOR,
APPLICATION FILED JUNE 27, 1917.

1,305,254.

Patented June 3, 1919.

UNITED STATES PATENT OFFICE.

CLAUD J. CLEFTON AND GUY J. CLEFTON, OF OWATONNA, MINNESOTA.

ACETYLENE-GENERATOR.

1,305,254.

Specification of Letters Patent. Patented June 3, 1919.

Application filed June 27, 1917. Serial No. 177,262.

To all whom it may concern:

Be it known that we, CLAUD J. CLEFTON and GUY J. CLEFTON, citizens of the United States, residents of Owatonna, county of 5 Steele, State of Minnesota, have invented certain new and useful Improvements in Acetylene-Generators, of which the following is a specification.

The object of our invention is to provide 10 improved means for mounting an auxiliary carbid hopper in the gas bell to the end that it may be conveniently removed for refilling when desired and air excluded from the generator during the operation.

15 The invention consists generally in various constructions and combinations, all as hereinafter described and particularly pointed out in the claims.

In the accompanying drawings forming 20 part of this specification,

The figure is a vertical sectional view through a generator embodying our invention.

In the drawing, 2 represents the generating tank, having a water chamber 3 within which a sleeve 4 is arranged, supporting a carbid hopper 5. 6 is the gas bell having its lower end immersed in the liquid seal within the annular chamber 7. 8 is a water supply 25 pipe through which fresh water is introduced to the tank, 9 is a pipe wherein the operating rod 10 for the agitating device 11 is mounted. 12 is a pipe containing a similar rod connected with the agitating device 30 13, the upper part of the pipe 12 having means for connecting a pump thereto for withdrawing the water and sludge from the bottom of the tank. 14 is a gas service pipe, connected with a pipe 15 located within the 35 40 tank and having a filter 16 within the gas bell, through which the gas flows to the service pipe.

The generator has the usual cover 17 and a space 18 beneath the cover and above the 45 bell which permits the rise and fall of the bell in the operation of the machine. 19 is the top of the carbid hopper, having an opening 20 therein, and 21 is a sleeve mounted on said cover and encircling said 50 opening. A second sleeve 22 is carried by the gas bell and telescopes with the sleeve 21. The sleeve 22 has the function of directing any moisture which may collect thereon down past the upper end of the sleeve 21 and 55 prevent it from entering the carbid hopper. The auxiliary carbid hopper has a jacket 23

provided with a flange 24 to rest upon the top of the gas bell, the lower end of said jacket fitting within the opening in said bell and the sleeves 21 and 22. The lower end of 60 the jacket 23 extends below the top of the sleeve 21 and prevents any possibility of carbid lodging on the top of the sleeve 21 or between it and the sleeve 22, all these details of construction contributing to a more perfect 65 operation of the machine and eliminating the danger which might result from spilling of the carbid around the top of the hopper. The hopper 25 has a double cone-shaped lower end 26 and a valve 27 is provided for closing the opening and has a stem 28 which projects through the cover 29 for said hopper and has a threaded end and a stuffing box 30 therein for preventing any 70 escape of gas. The cover 29 is arranged to 75 bear on the jacket 23 and a yoke 31 has a hook at one end for engaging a lug 32 on said jacket and a thumb screw 33 at its opposite end that is tapped into a lug 34 on the other side of said jacket. The middle portion 80 of this yoke bears at 35 on the center of the cover and when the thumb screw is tightened, the cover will be squeezed down to clamp it on the jacket and prevent the entrance of air and escape of gas through the 85 top of the auxiliary carbid hopper. To remove this hopper, it is only necessary to take off the cover 17 and lift the jacket and hopper out of the bell, when the hopper may be 90 refilled and replaced in the bell, ready to 95 discharge its contents into the main hopper beneath in case the supply of gas is low at a time, such as in the evening, when it is not convenient to empty the generator and refill it.

In various ways the details of construction herein shown and described may be modified and still be within the scope of our invention.

We claim as our invention:

1. An acetylene gas generator comprising a tank adapted to contain a supply of water, a carbid hopper therein, a gas bell encircling said hopper, the top of said hopper and said bell having oppositely arranged 105 openings therein, sleeves mounted on said hopper and said bell respectively and encircling said openings and arranged to telescope with the rise and fall of the gas bell, said hopper sleeve being seated against the 110 top of the bell and said bell sleeve being seated against the top of the hopper when

the bell is in its lowered position, thereby sealing the bell against the escape of gas or the entrance of air therein.

2. An acetylene generator comprising a tank, a carbid hopper therein, a gas bell encircling said hopper, the top of said hopper and said bell having openings oppositely arranged therein, sleeves mounted respectively on said bell and said hopper in telescoping relation, and an auxiliary carbid hopper removably fitting within the opening in said bell and within said sleeves.

3. An acetylene gas generator comprising a tank, a carbid hopper therein, a gas bell, said hopper and said bell having oppositely arranged openings, telescoping sleeves encircling said openings and an auxiliary carbid hopper removably mounted in the opening in said gas bell and depending within said sleeves and having a discharge opening and valve therefor accessible through the top of said tank.

4. An acetylene gas generator comprising a tank, a carbid hopper therein, a gas bell, said hopper and said bell having oppositely arranged openings therein, a jacket fitting within said opening and having a flange to bear on the wall of said bell around the opening therein, an auxiliary carbid hopper fitting within said jacket, means for clamping said auxiliary hopper on said jacket, said auxiliary hopper depending within said jacket and having a valve opening and a valve operated through the top of said jacket and auxiliary hopper, said jacket and said auxiliary hopper being removable from said bell for filling said hopper at a point remote from said generator.

5. An acetylene gas generator comprising a tank, a carbid hopper therein having a closed top provided with a filling opening, a gas bell encircling said hopper and also having an opening therein opposite the opening in said hopper, sleeves mounted re-

spectively on said hopper and said bell and 45 encircling said openings and in telescoping relation, and an auxiliary carbid hopper mounted on said gas bell and fitting within said sleeves and having a discharge opening and valve therefor.

6. An acetylene gas generator comprising a tank adapted to contain a supply of water, a carbid hopper therein having a closed top, a gas bell encircling said hopper and having a liquid seal, said hopper and said bell 55 having oppositely arranged openings therein, an auxiliary carbid hopper fitting within said openings and having means for discharging the carbid therefrom into the hopper of said generator, said auxiliary hopper being removable from said bell for filling it at a point remote from the generator, and means encircling the openings in said bell and generator hopper for sealing said hopper and said bell against the entrance 60 of air and the escape of gas when said auxiliary hopper is removed.

7. An acetylene gas generator comprising a tank adapted to contain a supply of water, a carbid hopper therein having a closed top, 70 a gas bell encircling said hopper and having a liquid seal, said hopper and said bell having oppositely arranged openings therein, an auxiliary carbid hopper fitting within said openings and having means for discharging the carbid therefrom into the hopper of said generator, said auxiliary hopper being removable from said bell for filling it at a point remote from the generator, and telescoping sleeves encircling the openings 75 in said bell and generator hopper for sealing said hopper and said bell against the entrance of air and the escape of gas when said auxiliary hopper is removed.

In witness whereof we have hereunto set 85 our hands this 18 day of June 1917.

CLAUD J. CLEFTON.
GUY J. CLEFTON.
